UNITED STATES PATENT OFFICE.

WARREN M. BAECHTEL, OF HAGERSTOWN, MARYLAND.

ROTARY BRUSH.

1,236,249.

Specification of Letters Patent. Patented Aug. 7, 1917.

Application filed February 18, 1917. Serial No. 149,518.

To all whom it may concern:

Be it known that I, WARREN M. BAECHTEL, a citizen of the United States, residing at Hagerstown, in the county of Washington and State of Maryland, have invented new and useful Improvements in Rotary Brushes, of which the following is a specification.

This invention relates to tooth brushes 10 and more particularly to brushes of the rotatable type.

An object of the invention is to provide a tooth brush which is capable of being rotated so as to brush the teeth with an up 15 and down motion as well as across the same, means being provided to rotate the brush with the same hand by which it is held.

Another object is to provide a brush 20 which is capable in addition to the action above mentioned of brushing the teeth with a stirring or angular motion, the brush for this purpose being of spiral formation.

A further object is to provide a brush of the above description which is capable of 25 being reversed, so that it may be operated with either hand to conveniently brush the teeth in either side of the mouth.

Other objects and advantages of the invention will appear from the following description, when taken in connection with the accompanying drawings, in which:

Figure 1 is an elevation of a tooth brush embodying the present invention;

Fig. 2 is a central sectional view of the 35 same;

Fig. 3 is a transverse sectional view on the line 3—3 of Fig. 2;

Fig. 4 is a similar view on the line 4—4 of Fig. 2;

Fig. 5 is an elevation of a modified form 40 of the invention;

Fig. 6 is an elevation of a still further modification;

Fig. 7 is a longitudinal sectional view of 45 the subject matter of Fig. 6.

Referring to the drawings in detail the invention comprises a casing of preferably cylindrical shape, the said casing being formed in sections and designated by the 50 numerals 10 and 11. The section 10 is formed with an elongated opening 12 and adapted to extend through this opening is a brush 13, which is longitudinally mounted within the casing.

55 This brush is of spiral formation as shown

and is formed or mounted upon a shaft 13', one end of which is journaled in the end 14 of the section 12, while its opposite end is journaled in a sleeve 15 located within the said section 12 and extending beyond the 60 same, the said sleeve being secured to and forming a part of the section 11 of the casing. The end of the shaft within the sleeve 15 has secured thereon a pinion 16, the sleeve being recessed as shown at 17 for this 65 purpose. If desired this recess may be provided with a plug 18.

Extending transversely of the casing and housed therein, is a rack bar 19, this rack bar being adapted to engage the pinion 16 70 for the purpose of rotating the same, and to this end the said rack bar is provided with a finger piece 20. The opposite end of the rack bar is provided with a head 21, against which is adapted to bear a spring 22, 75 the said spring being housed within a tubular casing 23 secured to and extending laterally from the sleeve 15.

It is thus apparent that the brush may be 80 grasped in the hand and the rack bar operated by the thumb or finger of the said hand for the purpose of rotating the brush.

In order to provide for the convenient use of the brush by either hand, so that the teeth in each side of the mouth may be 85 cleaned, the section 10 is rotatably mounted upon the sleeve 15 or upon the section 11, of which the sleeve is a part. In order to accomplish this it is only necessary to give the section 10 a half turn with respect to the 90 section 11, when the opening 12 will be locked in a position for convenient use by the opposite hand. The section 10 is yieldingly held in position by means of lugs 24 formed upon the sleeve 15, which are adapted to engage notches 25 formed in the section 10, the said lugs being held in their adjusted engagement by means of a spring 26 which surrounds the sleeve 15 and bears against the flange 27 of the section 10 and a 100 disk 28, which is removably secured to said sleeve. If desired the end of the section 11 may be provided with a removable cap 28' as shown.

Various changes in the form and proportion of the invention may be made, as for example as shown in Fig. 5 a leaf spring 29 may be secured to the casing as shown at 30 and engaged to the underside of the finger piece 20, in place of the spring 22 previously 110

described. In other respects this form of the invention is the same as illustrated in the preceding figures.

A further modification of the invention is illustrated in Figs. 6 and 7. In this form the shaft of the brush is extended and is of spiral formation as indicated at 31, the said extended end of the shaft having a bearing in a disk 32 within the casing. Mounted 10 upon the spirally formed shaft 31 is a finger piece 33, which extends laterally through slots 34 provided upon diametrically opposite sides of the casing, so that a longitudinal movement of this finger piece will rotate the said shaft and consequently the brush. Interposed between the finger piece 33 and the disk 32 is a spiral spring 35, the purpose of this spring being to return the finger piece after it has been forced along the shaft 20 against the action of the spring.

It is believed from the foregoing description and accompanying drawings that the construction, operation and advantages of

the invention will be readily understood by persons skilled in the art and that a more 25 extended description is therefore unnecessary.

Having described the invention, what is claimed, is;

The combination with a brush, of a casing 30 embodying a plurality of tubular sections of equal diameters, a sleeve secured in the inner end of one of said sections and provided with a reduced portion extending within the other section, an abutment carried at the extremity of the reduced portion of said sleeve, an inwardly extending flange located at the inner end of the other section and surrounding the reduced portion of said sleeve, a spring interposed between said flange and 40 said abutment and means carried by one of the sections and engageable with the other section for holding the said sections against accidental rotation.

In testimony whereof I affix my signature. 45
WARREN M. BAECHTEL.
